CLAIM

The ornamental design for a pair of leveling ladder leg attachments, as shown and described.

DESCRIPTION

FIG. 1 is a perspective view of a pair of leveling ladder leg attachments.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view of the pair of leveling ladder leg attachments.

FIG. 7 is a bottom plan view thereof; and,

FIG. 8 is an alternate perspective view of the pair of leveling ladder leg attachments in full lines with a ladder shown in broken lines representing environmental association matter being for illustrative purposes only and forming no part of the claimed invention.
